SIGNALING DEVICE

Joseph P. Knipp, Long Beach, Calif.

Continuation of application Serial No. 352,908;
August 16, 1940. This application April 26,
1943, Serial No. 484,507

3 Claims. (Cl. 200—86)

The present invention relates to signaling devices and has particular reference to pneumatic actuating means for such devices. This application is a continuation of my copending application, Ser. No. 352,908, filed August 16, 1940.

It is the general object of my invention to provide a simple and inexpensive device for actuating light or bell signals in response to pressure against a collapsible portion of the device. It is a further object to provide pneumatic actuating means which will not readily get out of order, but will give perfect service over a long period of time without special attention on the part of the user thereof.

To this end, the invention resides in the combinations illustrated in the accompanying drawings, a detailed description of which follows, and the invention is particularly defined in the claims hereto appended.

In the drawing:

Fig. 1 is a front view of a control box within which the device of my invention is shown mounted, the cover of the box being partly broken away in order to expose the essential features thereof;

Fig. 2 illustrates a slightly modified form of the invention; and

Fig. 3 illustrates a signal sounding device adapted to be actuated by either one of the aforementioned devices.

Referring in the first instance to Fig. 1, it is noticed that a tubular stem 2 is seated within a casing 1, and that a cylindrical plunger 3 is fitted to slide axially within this stem. This plunger terminates in a contact member 4, in axial alignment with a second contact member 5, and the latter is mounted for axial adjustment within a boss 6 of the casing 1.

The stem 2 projects beyond the end of the casing to receive a resilient tube 7, the free end of which is suitably closed, as by a plug 8. Any one who drives an automobile is familiar with the rubber tube extending across the service driveway of gasoline dispensing stations for compression by the wheels of the entering car, thereby to actuate a signal, usually a gong, in order to direct the attention of the attendant to the entering car. The tube 7 represents such signal tube, and it is noticed that compression thereof by a vehicle wheel causes the plunger 3 to advance until the member 4 contacts the member 5.

Fig. 3 shows a circular casing 10, within which a solenoid magnet 11 is mounted, and this magnet is fitted with a plunger 12 which, in turn, is axially aligned with the edge of a bell or gong

13. The latter is suitably mounted in the casing, as by means of a bracket 14. A circuit 15 extends from a source of electric energy 16, through the contact members 4, 5, to the solenoid magnet, thereby to energize this magnet when contact is made by compression of the tube 7, and to cause the plunger 12 to advance until it strikes the gong.

In practice, a transformer is cut into the circuit, but as such transformer is commercially used in such devices and forms no part of the present invention, it is not illustrated in the drawing. Suitable insulation for the contact members must, of course, be provided. The boss 6 may, to the end, be made from insulating material. The stem 2 is shown fastened to the casing by means of a bracket 18, which also conveniently may be made from insulating material or otherwise insulated from the stem. Insulating bushings 19, 20, 21 are preferably provided in order completely to insulate the casing and protect the device from short circuits.

It was above stated that compression of the tube 7 causes the plunger to advance. This, of course, is necessary in order to close the circuit. But it is equally important that the plunger is positively retracted so as to break the circuit quickly and thereby to prevent fusing of the contacts. In order to make certain that the plunger is quickly and positively retracted by suction of the expanding tube after pressure thereagainst is relieved, it is necessary to fit the plunger within the stem with great exactness. If any leakage takes place during operations of the device, no clean break of the circuit will be effected and the contact may not even be made. When the plunger is properly fitted, it will function satisfactorily no matter in what direction the casing is mounted.

40 The device of Fig. 2 is, so far as functioning is concerned, exactly a duplicate of the one above described. Structurally, the difference is chiefly that the plunger portion is greatly enlarged in diameter, and this is done in order to provide a 45 more sensitive switch actuating device. The tubular member 7 is, in this drawing, shown attached to a nipple 31, of a cylindrical cup 32, seated within the casing 30, and this cup takes the place of the stem 2 of Fig. 1. The plunger 50 in this case takes the form of a cylindrical cap 33, which is carefully machined and fitted to slide axially on the cup. So far as normal operation is concerned, this plunger element might as well be fitted to slide within the cup, in similarity with the plunger 3 of Fig. 1, and the 55

principal reason for mounting it on the outside thereof is to form a better protection against dirt and dust entering the cup.

Because of the larger diameter, the air entering the cup in response to compression of the tube 7, has more time to expand and so moves the cap 33 forward more slowly and gently, thereby avoiding the hammer blow effect of a small diameter plunger such as shown in Fig. 1. This is a distinct and very important advantage. The contact mechanism may, in this case, remain as above described but, because of the greater sensitiveness of this construction, I have found it preferable to employ a switch mechanism comprising resilient fingers 34, 35 terminating in contacts 36, 37. An insulating plug 38 is seated in the cap 33 to impart the slight movement necessary to close the circuit through these contacts. It is well to provide backing for the finger 35, and such backing here takes the shape of a pad 39, made from insulating material. It is shown mounted on a stud 40 which is axially adjustable in the casing properly to space the contacts apart.

The contact fingers are shown mounted on a post 41 of the casing, and they are insulated therefrom, as by means of rubber or fibre bushings 42, 43, 44, but other suitable mounting means may be substituted, if preferred. The casing 30 should also be provided with a tightly fitted cover in order to exclude all dirt and dust therefrom, but for the sake of clearness, only a corner of such cover is indicated at 45, and means such as screws 46, 47 are employed to mount the cover tightly in position.

I am aware that other devices have been developed for closing a circuit in response to compression of a tube such as here considered, but no such device has come to my attention at the present, in which telescoping members are so delicately fitted for relative axial movement that they will positively expand and contract by pressure and suction within the tube without the aid of other actuating or control mechanism.

The drawing is merely illustrative of the invention, and it is not my intention to be limited to the exact arrangements and proportions of parts shown and described, but I reserve the right to embody further modifications within the scope of the claims hereto appended.

I claim:

1. A pneumatically actuated signaling device comprising, a casing, a cylindrical cup of relatively large diameter seated within said casing,

a cylindrical cap carefully fitted to slide axially on said cup, a compressible resilient element of relatively small diameter extending from said cup to form an air chamber communicating with the space within the cup and cap, compression and expansion of said element alone causing said cap to reciprocate axially on the cup, a post mounted within the casing adjacent said cap, a normally open circuit terminating within the casing in resilient electric contact members mounted on and insulated from said post, and an insulated element on the cap adjacent one of said members adapted to move the member against the other member in response to expansive movement of the cap thereby to close said circuit.

2. A pneumatically actuated signaling device comprising, a cylindrical cup of relatively large diameter, a cylindrical cap carefully fitted to slide axially on said cup, a compressible resilient element of relatively small diameter extending from said cup to form an air chamber communicating with the interior space within the cup and cap, compression and expansion of said element alone causing said cap to reciprocate axially on the cup, a post mounted adjacent said cap, a normally open circuit terminating in resilient electric contacts mounted on and insulated from said post, an insulated stop for one of said contacts, and an insulated element on said cap adjacent the other contact and adapted to move it against the first named contact in response to expansive movement of the cap thereby to close said circuit.

3. A pneumatically actuated signaling device comprising, a casing, a cylindrical cup of relatively large diameter seated within said casing, a cylindrical cap carefully fitted to slide axially on said cup, a compressible resilient element of relatively small diameter extending from said cup to form an air chamber communicating with the space within the cup and cap, compression and expansion of said element alone causing said cap to reciprocate on the cup, a post mounted within the casing adjacent said cap, a normally open circuit terminating in resilient contact members mounted on and insulated from said post, an insulated stop in the casing for one of said members, adjusting means for said stop, and an insulated element on said cap adjacent the other member and adapted to move the latter against the first named member in response to expansive movement of the cap thereby to close said circuit.

JOSEPH P. KNIPP.
